UNITED STATES PATENT OFFICE.

FRANK TEIJIRO KOBAYASHI, OF KENILWORTH, UTAH.

ELECTRICAL SWITCH.

1,246,282.

Specification of Letters Patent. Patented Nov. 13, 1917.

Application filed January 17, 1916. Serial No. 72,475.

To all whom it may concern:

Be it known that I, FRANK T. KOBAYASHI, a citizen of the Japanese Empire, residing at Kenilworth, in the county of Salt Lake 5 and State of Utah, have invented certain new and useful Improvements in Electrical Switches, of which the following is a specification.

This invention has for an object to provide an improved form of electrical switch, and especially one fitted for use with the familiar "pull cord," although it is adaptable to operation by other means, as will be readily understood. It is an important aim 15 to provide a device of this kind adapted to be incorporated in the canopy of familiar forms employed in ceiling and wall fixtures. It is therefore an especially important aim to provide a device of this kind 20 which can be compactly embodied in an annular space of limited size.

An important purpose of the invention is to enable the installation without complication of structural details of fixtures 25 ordinarily employed at present, and among additional objects and advantages are the following:

To provide a novel skeleton or frame of insulating material for carrying the parts 30 of the switch. The provision of an improved form of oscillating switch element. A novel means for operating the switch, combining the elements of safety and efficiency, the operating means being effectively 35 insulated from the switch, and the operation of the device being extremely positive, simple and easy. Novel construction of switch terminal parts of utility. Novel assembly relation of the parts whereby great 40 economy in the construction and assemblage of the switch is attained, while making all parts easily accessible.

Additional objects, advantages and features of invention will appear from the construction, arrangement and combination of parts hereinafter set forth and shown in the drawings, where,

Figure 1 is an elevation of the switch installed, with a portion of the canopy broken 50 away,

Fig. 2 is a similar view at right angles to Fig. 1,

Fig. 3 is a detail elevation of the switch, detached, with its cover,

55 Fig. 4 is a top view of the switch, detached, with the cover thereon,

Fig. 5 is a horizontal section on the line 5-5 of Fig. 1,

Fig. 6 is a detail of the rocking wheel,

Fig. 7 is a detail of the crank member, 30

Fig. 8 is a detail of the switch arm with the slide bearing element removed,

Fig. 9 is a similar view of the switch arm with the slide bearing in place,

Fig. 10 is a detail of the switch arm assembly, 35

Fig. 11 is a perspective of the double switch contact element,

Fig. 12 is a similar view of the single switch contact element, 40

Fig. 12a is an end view of the last named element,

Fig. 13 is a detail elevation of the switch pivot frame,

Fig. 14 is a diagram of the wiring, 45

Fig. 15 is a side view of the bracket for the switch actuator,

Fig. 16 is a perspective view of the insulating block,

The parts are shown full size. 50

There is illustrated a crow foot 10 of familiar form, into which is screwed a fixture pipe 11 of the ordinary kind. Over the lower part of the pipe 11 the ornamental tube 12 customarily of brass is engaged, and upon this is slidable the collar 13 of the canopy 14 which is shown in a shape and size formally approximating that of the canopies usually employed in such situations. The canopy is held in place by the 55 customary set screw 15 engaged through the collar 13.

The foundation body for the switch in the present instance comprises two porcelain annuli 16 and 17 respectively carried at the top and bottom of a cylinder 18 of similar material interposed therebetween. The annuli 16 and 17 are held together by certain switch elements to be described. At one side of the switch an actuator frame 19 is mounted, having an outer vertical portion 20, the upper part of which is offset beginning at a point about one third its height from the bottom, and two inwardly extending arms 21 at top and bottom respectively, drilled and tapped to receive the assembly screws 22 engaged through the porcelains 16 and 17. The offset portion is thickened at its lower part, which is approximately midway of the height of the frame, as at 23, the thickened portion 11 being tapped to receive a pintle screw 24 which projects a distance inwardly of the

inner part of the vertical piece 20, the inner end of the screw being formed with a small bearing 25, the adjacent outer portion of the screw being cylindrical and smoothly finished to form a bearing for a rocker wheel 26. This wheel 26 is provided on the side next the frame 19 with check blocks 27 diametrically spaced and shaped to engage opposite sides of the lower vertical portion 20 5 alternately under rotary oscillation through an arc of 90 degrees. A helical torsion and expanding spring 28 is confined between the upper offset portion of the part 20 of the frame 19 and the wheel 26, having one end 10 engaged over the shoulder 29 formed at the lower part of the offset, and its other end engaged with one of the blocks 27. By this spring the wheel is pressed inwardly against the crank wheel 30, engaged revolvably on the bearing 25, the rocker wheel being provided 15 in its outer face with ratchet notches 31 in which suitable ratchet teeth 32 formed on the inner side of the wheel 26 may engage, there being four of the notches equally spaced on the crank wheel. At its inner side a crank pin 33 is provided, suitably located on the wheel 30 for the purposes to be described.

In a plane parallel to the wheels before mentioned, the cylinder 18 may be flattened 20 as at 34, if desired. A switch pivot frame 35 is provided, having a lower plate 36 secured to the bottom portion 17, its outer end 37 being turned upwardly in a plane spaced slightly outward of the flattened side of the cylinder and parallel thereto, being apertured and receiving a pintle screw 38, upon which a switch arm 39 is pivoted, having a block 40 of insulating material fixed therein and formed with a longitudinal slot 41 receiving the crank pin 33, as shown, the block serving as a stop for the wheels 26 and 30 which are forced theretoward by the spring 28 before mentioned. The slot 41 in the block 40 is lined with a thin steel slide bearing collar 42, conforming to the shape of the slot, and extending from one side to the other of the block. The pivot frame 35 extends upwardly adjacent the opposite side of the cylinder 18 from the switch, as at 44, (Fig. 2) a binding screw 45 being provided centrally thereof in a suitable inset portion 46 upon the frame, and at the upper part an arm 47 is run horizontally, tapped to receive the assembly screw 48 engaged through the upper porcelain. The lower plate 36 similarly receives screws 48'. The frame piece 35 may be formed of one strip of sheet metal bent to the conformation shown.

The switch arm 39 is formed of one piece 60 of sheet metal, having at its base a rectangular piece 49, suitably apertured to receive the pintle screw 38, its intermediate portion being formed with an offset arm 49', extending from the arm 37 to the base of a contact tongue 39', at one side, while at the other the

intermediate portion comprises a swinging arm similarly joined to the tongue 39', but free at its inner end, extending diagonally outward, but adapted to be pressed inwardly against the rectangular piece 49, forming 70 thereby an enlarged oblong opening 51 in the arm 39. The insulator block 40 is shaped to conform to the shape of this opening 51 when the arm 50 is pressed to its innermost position, and the block is grooved, peripherally, the base of the groove corresponding in size to the size of the opening 51, while the outer parts provide flanges which engage the sides of the switch arm to prevent displacement of the block. The parts of the switch 75 arm described are held in engaged position by means of a small yoke 53, comprising simply a small rectangular plate of sheet metal having edge portions turned upwardly so as to receive the base 49 and arm 50 snugly 80 therebetween when pressed together, and being apertured in register with an aperture through the base 49 to receive the pintle screw 38, which is threaded in the upstanding arm 37 of the frame 35, a lock nut 54 85 being engaged on the end of the pintle screw 38 to prevent it from turning. The outer end of the tongue 39' of the switch is bent inwardly at right angles to form a contact piece co-operating with contact points to be 90 described.

At the opposite side of the appliance from the frame 35 a two point contact element is provided, comprising a vertical bar 60 spaced a short distance inwardly from the 100 plane of the switch arm 39, located closely adjacent the cylinder 18, and having at top and bottom outwardly extending plates 61 and 62 respectively, the last named having its outermost portion turned up and extended a short distance at an inclination and curved slightly outward to receive the contact piece on the switch arm when at the lower limit of its movements, as at 63. The plate 61 has a contact tongue 64 of a similar form thereon directly above the one 63, and positioned to engage the contact piece on the switch arm when at the upper limit of its movement. The plate 61 extends across the under side of the upper porcelain 110 16 in a direction at right angles to the plane of the switch arm, and its extremity is turned down and provided with a binding screw 65, by which suitable wiring connections may be made. The plates 61 and 62 115 are tapped at 61' and 62', to receive assembly screws, by which the two point element may be attached to the upper and lower porcelains 16 and 17 respectively.

Mounted on the lower porcelain 17 spaced 125 outwardly of the plate 62 from the plane of the switch, there is a one point contact element 70. This includes the horizontal plate 71 secured by the assembly screw 72 to the lower porcelain as shown, a vertical inset 130

portion 73 having the binding screw 74 therein, and a lateral extension 75, projected toward the switch so as to lie in close engagement and overlapped relation with the 5 end of the switch when in an intermediate position, the extremity of the extension having outwardly turned lips 76 to allow proper sliding of the switch end thereon.

The lower porcelain 17 is formed with a 10 diagonal passage 80 therethrough, on a line extending above the lower plate 21 of the actuator frame, and running downward. The passage opens through a beveled face 81 adjacent the edge of the lower porcelain, on 15 its under side. The lower plate 21 of the actuator frame is provided with an extension 83, bent upwardly to lie in a plane at right angles to the axis of the passage, and is formed with a threaded opening conforming to the size of the passage, in which there 20 is threaded the inner end of a guide tube 84, having a flared lower end, through which there is engaged the cord 85 such as is customarily used in pull switches, a suitable 25 ball 86 being attached to its lower end, while the upper end of the cord is passed partly around the wheel 26 and attached thereto, so that upon pulling the cord the wheel will be rotated against the action of the spring 28.

30 In use, the parts of the fixture, before attachment to the crow foot or hickey, are assembled in the customary manner, the ornamental tube 12 being cut off short enough to leave a portion of the pipe 11 projecting 35 thereabove to allow a metal retaining collar 90 to be slipped thereon and the porcelain skeleton of the switch engaged thereover, leaving a part of the pipe projecting above the switch skeleton for engagement with the 40 crow foot or hickey. If desired, a dust cap 91 may be provided to engage over the switch, the cap comprising a cylinder of paper with a top piece 92 having an enlarged opening therethrough, at its center, and provided with the necessary number of openings 45 93 therearound to receive wires passing to the switch. In the present instance, a three wire switch being shown, three small openings are formed in the cap, and either 50 before or after engagement of the wires with the proper binding screws, the switch may be engaged on the upper end of the pipe 11. After the wires have been connected the dust cap is adjusted in position 55 and the pipe 11 screwed into the crow foot or hickey, as the case may be. In the initial adjustment of the device the guide tube is detached, and after the switch is secured in place in any well known way, the guide is 60 engaged through a suitable aperture in the canopy, inserted through the passage 80 and engaged with the apertured lug 83 of the actuator frame. The cord in the initial assembly operation is permanently attached to 65 the wheel 26, without the ball at its outer

end, so that the cord may be readily inserted through the opening through the canopy, and the guide tube, after which the ball is attached.

The use of the switch will be readily understood by those working in the art, but it may be stated that in the present embodiment of the switch one wire 95 is led from the lamp socket or circuit in the fixture to the binding screw 45 on the pivot frame, 70 while from the other side of the socket or circuit in the fixture the wire 96 leads directly to the main line circuit. From the contact 70 as shown in the diagram a wire 97 leads to a similar contact element in a wall 80 switch 98, diagrammatically illustrated, and from the binding screw 65 a wire 99 leads to a corresponding terminal 100 on the 3-point wall switch of familiar construction for operation, from the switch arm 101 of 85 which the main line wire 102 extends. This construction permits the light to be controlled by either switch alternatively.

It will be seen that an extremely simple construction of switch is provided adapted 90 to be incorporated in a very small annular space, the central portion of the device being left clear for the passage of the fixture pipe and suitable insulating wall to circumscribe the pipe, and at the same time an efficient switch mechanism of an economical 95 construction is presented. With the exception of the upper part of the actuator frame, all metallic elements of the switch proper, binding posts and operating parts alike are 100 contained within the projection of the boundaries of the upper and lower porcelains 16 and 17 in the direction of their axis. By beveling the lower porcelain at the lower 105 side, it is adapted to conform to the shape of the canopy in case of a close fit. At the same time there is ample accommodation for connections and portions of wire which are required to project through the crow foot or hickey. 110

What is claimed:

1. A switch of the class described comprising an annular insulating body, a switch arm mounted thereon for oscillation in the mean direction of the axis of the annulus, 115 and within a projection of the annulus in the direction of its axis, and without the like projection of the edge of the orifice of the annulus, contact means fixed upon the annulus laterally of the switch arm between 120 said projections, means for making electrical connections with the switch and contacts, and means to operate the switch.

2. A switch of the class described comprising concentric upper and lower annular foundation elements, an actuator frame secured therebetween at one side between projections of the periphery of the annuli and their orifices concentric with their axis, a switch element pivoted on the frame for oscillation be- 125 130

- 5 between said projections, and located close to the projection of the orifices, a switch operating mechanism beside said switch within the space between said projections, contact and terminal elements carried between the annuli within the space between said projections in coöperative association with the switch element, and means for making electrical connections with the switch.
- 10 3. In a switch, a switch body having an enlarged opening therethrough, one side portion of the opening being disconnected, a grooved block of insulating material shaped to conform to and engaged in said opening 15 with the edge portions around said opening engaged in the groove, said block constructed for engagement of an operating member, and means to hold the side portion of the body snugly engaged in the groove of the 20 block.
4. In a switch, a switch body comprising a base plate, a side portion, an outer portion, and an inwardly projecting portion in spaced relation to the said side portion; a 25 peripherally grooved block between the said side portion and the said inwardly extending portion and receiving the two last

mentioned portions in its groove, a plate having inturned edge portions engaging the extremity of said inwardly extending portion and the far side of the switch body, and means to secure said plate to the body.

5. A switch of the class described comprising upper and lower annular insulator bases, a concentric cylindrical element therebetween, a pivot frame extending therebetween and attached to each of the bases and having an extension provided with a terminal binding device, a switch arm pivoted on the pivot frame in a plane at right angles to 40 said extension, an actuator frame beside the switch connected to said insulator bases, means on the last named frame to operate the switch arm, a contact element at the side of the device opposite the pivot frame also 45 connected to the insulator bases, and means to hold the switch on a pipe inserted through the insulator bases.

In testimony whereof I have affixed my signature in presence of two witnesses.

FRANK TEIJIRO KOBAYASHI.
